UNITED STATES PATENT OFFICE

111,621

DESIGN FOR A WALLET

Leopold G. Stanley, Maplewood, N. J.

Application November 24, 1937, Serial No. 73,159

Term of patent 7 years

To all whom it may concern:

Be it known that I, Leopold G. Stanley, a subject of the King of England, residing at Maplewood, in the county of Essex, State of New Jersey, have invented a new, original, and ornamental Design for a Wallet, of which the following is a specification, reference being had to the accompanying drawing, forming a part thereof.

Fig. 1 is a face or front elevational view of a wallet in which my new design is embodied.

Fig. 2 is an edge elevation thereof.

Fig. 3 is a front perspective view thereof in open position.

The back of the article, not shown, is substantially plain except for a peripheral edge appearance substantially the same as the illustrated peripheral edge appearance at the front of the article.

I claim:

The ornamental design for a wallet, substantially as shown and described.

LEOPOLD G. STANLEY.
